UNITED STATES PATENT OFFICE.

JOHN GEARY, OF PHILADELPHIA, PENNSYLVANIA.

ELECTRIC ANNUNCIATOR.

SPECIFICATION forming part of Letters Patent No. 349,580, dated September 21, 1886.

Application filed March 6, 1886. Serial No. 194,291. (No model.)

To all whom it may concern:

Be it known that I, JOHN GEARY, a citizen of the United States, residing at Philadelphia, in the county of Philadelphia and State of Pennsylvania, have invented certain new and useful Improvements in Electric Annunciators; and I do hereby declare the following to be a full, clear, and exact description of the invention, reference being had to the accompanying drawings, which form part of this specification, in which—

Figure 1 is a front elevation of an annunciator, showing the parts in their normal position, with the exception of one of the drops, which is represented as having fallen, the guide-rods being represented as down. Fig. 2 is a front elevation with all the drops raised and the guide-rods elevated. Fig. 3 is a side elevation, the side of the annunciator-case being represented as partly broken away, the full lines showing the normal position of the guide-rods and the dotted lines the elevated position of the guide-rods.

My invention has relation to electric annunciators, and my improvements have for their object to provide a construction in which sliding drops are employed, said drops moving on guide-rods, and the rods being vertically movable and serving as lifts for the drops.

My improvements consist, essentially, in the combination, with the sliding drops of an electric annunciator, of a rod or rods which forms a guide or form guides for such drops, said rod or rods being movable vertically and operating as a lift or as lifts for such drops, as hereinafter fully described.

Referring to the accompanying drawings, A represents an electric annunciator case or box having electro-magnets B B, and sliding armatures b b, said magnets and armatures being preferably constructed and mounted in the manner shown and described in my application for Letters Patent of the United States filed November 25, 1885, Serial No. 183,932.

C C are sliding drops, which are sustained in their normal elevated position when the magnets are inert, said drops then resting on the armatures b b. When the magnets are energized and the armatures attracted, the drops are deprived of their armature-supports and

fall or slide down on their guide-rods D D until they meet the pins or studs d d in said rods. To lift the drops, the guide-rods are moved upwardly, carrying the drops that have fallen with them until the flanges of said drops, which flanges are marked e, pass above the lower edges, b', of the armatures. The rods D are then allowed to fall, and they slide downwardly, the drops remaining arrested on the armatures.

If desired, each of the guide and lift rods may be moved separately; but I prefer to move them together, and to this end connect them by a cross-piece, E, and to this cross-piece I attach a push-rod, F, terminating in a button 65 or push, f, below the bottom of the case A.

The rods D are themselves guided in any suitable manner, preferably in the brackets G G', in which the post H is fitted, said post being the one on which the magnets are supported. The downward movement of the guide-rods is limited by the cross-bar E, meeting the bracket G', and their upward movement is limited by the button f, meeting the bottom of case A.

I am aware that sliding drops moving on stationary guide-rods have been heretofore proposed, and that annunciators have been made in which all of the drops could be lifted simultaneously by a single movement; but my invention differs from these in that in my construction the guide-rods for the drops are movable vertically and form lifts for such drops.

In small annunciators a single guide-rod may be sufficient for all the drops; but where a considerable number of drops are employed two or more guide-rods will be required. My invention, accordingly, includes one guide-rod or two or more such rods.

In the drawings I have illustrated an annunciator with two guide-rods, which fully exhibits my invention.

What I claim as my invention is as follows:

1. In an electric annunciator having sliding drops, the combination, with such drops, of vertically-movable rods, which form guides and lifts for such drops, substantially as shown and described.

2. The combination, with magnets B B, armatures b b, and sliding drops C C, of a ver-

tically-movable rod, D, having pins or stops
d d, said rod forming a guide and lift for said
drops, substantially as shown and described.

3. The combination, in an electric annunciator, of magnets B B, armatures *b b*, sliding
drops C C, vertically-movable guide and lift
rods D D, having pins or stops *d d*, cross-piece
E, connecting said rods, and push-rod F, said
parts being constructed and arranged for op-
eration substantially as shown and described.

In testimony that I claim the foregoing I have
hereunto set my hand this 4th day of March,
1886.

JOHN GEARY.
